UNITED STATES PATENT OFFICE

JAMES S. HALL, OF MOUNT PLEASANT, PENNSYLVANIA, ASSIGNOR TO L. E. SMITH
GLASS COMPANY, OF MOUNT PLEASANT, PENNSYLVANIA, A CORPORATION OF PENN-SYLVANIA

DESIGN FOR A VASE

Application filed March 31, 1932. Serial No. 43,351. Term of patent 7 years.

To all whom it may concern:

Be it known that I, JAMES S. HALL, residing at Mount Pleasant, in the county of Westmoreland and State of Pennsylvania, a citizen of the United States, have invented a new, original, and ornamental Design for a Vase, of which the following is a specification, reference being had to the accompanying drawing, forming a part thereof.

The figure is a front elevational view of the vase showing my new design.

I claim:

The ornamental design for a vase as shown.
JAMES S. HALL.
